UNITED STATES PATENT OFFICE.

GEORGE W. ALLEN, OF HYDE PARK, MASSACHUSETTS, ASSIGNOR TO B. F. STURTEVANT COMPANY, OF HYDE PARK, MASSACHUSETTS, A CORPORATION OF MASSACHUSETTS.

BLOWER.

Application filed August 18, 1923. Serial No. 658,132.

The present invention relates to blowers and more particularly to centrifugal blowers in which air or other fluid is taken in axially and discharged circumferentially.

5 The object of the invention is to provide a wheel for blowers of this general type which will be of strong mechanical construction and relatively simple in manufacture and adapted for operation at high speeds.

10 With this object in view, the invention consists of certain novel features of construction, combinations and arrangements of parts hereinafter described and particularly defined in the claims.

15 In the drawings Figure 1 is an elevation of a blower wheel embodying the several features of the present invention, certain of the parts being broken away; Fig. 2 is a section on line 2—2 of Fig. 1; Fig. 3 is a section on line 3—3 of Fig. 2; and Fig. 4 is an end view of one of the floats looking toward the center of the wheel.

The illustrated embodiment of the invention comprises a series of floats indicated 25 generally at 6 which are mounted between a pair of annular side plates 8 and upon a solid central forged disk 10 which is provided with an integral hub 12 bored to receive the driving shaft. The side plates 8 are of the usual form, each being preferably 30 pressed out of a single piece of sheet metal and arranged to converge toward each other at the outer periphery, as shown in Fig. 2. In order to avoid excessive strains and 35 stresses at the periphery of the disk 10 which would be developed at the high rotational speed of operation of this fan, the diameter of the disk is made substantially less than that of the complete fan wheel, being, in the 40 illustrated embodiment of the invention, about three-fourths of such diameter. The disk is also formed with a slight taper from hub to periphery. It will be obvious that due to the use of the solid supporting disk 45 the illustrated wheel is adapted to take in air from both sides and is therefore to be employed in a blower casing having an inlet at each side. In order to form a rigid construction, each of the side plates is provided with a binder ring 14 adjacent the inlet opening.

Each float 6 consists of a pair of blades 16, each blade having its inner side edge, i.

e. the side edge adjacent the disk 10, extended inwardly towards the axis well beyond 55 the outer side edge, thereby affording additional strength and support to the blade without reducing the diameter of the intake opening. Further strength and rigidity is afforded by the curvature of the blades 60 transversely of the axis of rotation as shown in Fig. 1 and by the opposite longitudinal curvatures at the inner and outer ends of the blade. The longitudinal curvature of the inner portion of the blade is convex toward 65 the direction of movement as shown in Fig. 3 and that of the outer portion of the blade is concave toward the direction of movement as shown in Fig. 4. Each blade is provided with an outer forwardly extending flange 70 or lip 18 for attachment to its corresponding side plate by a row of rivets 20, and an inner rearwardly extending flange 22 for attachment to the central disk by a row of rivets 24. As indicated in Fig. 2, the same 75 row of rivets 24 is employed to attach both flanges 22 of the pair of blades to the disk 10. It is desirable that corresponding pairs of blades 16 be positively secured together outside the periphery of the disk 10. To this 80 end, the opposing flanges 22 of each pair of blades are welded together from the point where they project from the edge of the disk 10 to the edge of the wheel. As indicated in the drawings, the tapered disk 10 is such 85 as to bring the outer ends of the flanges 22 normally close together so that the welding operation may be readily carried out, the space between the flanges being filled with the weld, as indicated at 26, in such a manner that a solid rigid float is obtained from each pair of blades. In order to provide further reinforcement for the wheel, a metal angle 28 is connected to the front of each 90 blade and to the disk by rivets 30. 95

It will be seen that the present invention provides a wheel which comprises few parts, may be easily constructed at a comparatively low cost, and is of exceptional strength. It is particularly adapted for high speed drive 100 as by a direct connected steam turbine.

While it is preferred to employ the specific construction and arrangement of parts shown and described, it will be understood that this construction and arrangement is 105 not essential except so far as specified in the

claims, and may be changed or modified without departing from the broader feature of the invention.

Having thus described the invention, what is claimed is:

- 5 1. A blower wheel comprising a pair of annular side plates, having large central openings for admission of air, a solid rotatable central disk between the side plates of a 10 diameter less than the outer diameter of the side plates and greater than their inner diameter, and a series of floats having flanges at their ends riveted to the disk and to the side plates, the inner portions of the floats 15 and the flanges thereon adjacent the disk extending inwardly beyond the inner margin of the side plates and near the center of the disk to provide additional riveting surfaces to the disk without obstruction of the air 20 admission openings of the side plates.
2. A blower wheel comprising a pair of annular side plates, a solid central disk between the plates and of an external diameter less than that of the side plates, and 25 floats secured to the plates and to the disk and extending outwardly beyond the periphery of the disk and inwardly beyond the inner margin of the side plates, the floats being longitudinally curved and without substantial transverse curvature for the 30 major portion of their length and transversely curved at their inner ends.
3. A blower wheel comprising a pair of

side plates, a solid central supporting disk of less diameter than the side plates, a series 25 of floats each consisting of a pair of blades and means for securing the blades to the plates and to the disk, each blade having its inner portion transversely curved and its inner and outer portions of opposite longitudinal curvature, respectively convex and concave toward the direction of movement.

4. A blower wheel comprising a pair of annular side plates having large central openings for admission of air, a solid rotatable disk between the side plates of a diameter less than the outer diameter of the side plates and greater than their inner diameter, a series of blades having flanges at each end for attachment respectively to the 45 plates and to the disk, the inner portions of the blades and the flanges thereon adjacent the disk extending inwardly beyond the inner margin of the side plates and near the center of the disk for attachment to the disk 55 without obstruction of the air admission openings of the side plates, and an angle piece secured to the disk and to each blade and extending in an opposite direction from the flange thereon to form a supplementary 60 oppositely turned flange to provide additional riveting surface for securing the blade to the disk.

GEORGE W. ALLEN.
